FITTED HANDBAG

Mary Herrera, New York, N. Y.

Application May 14, 1952, Serial No. 287,751

3 Claims. (Cl. 150—34)

1

This invention relates to new and useful improvements in fitted handbags.

More particularly, the present invention proposes the construction of an improved article holding side wall and bottom wall liner for a handbag which can be readily and easily inserted in a handbag to make a fitted bag.

Another object of the present invention proposes forming the side wall and bottom wall liner and an article holding center member pivotally connected together and constructed in such a manner that the center member can be tilted to either side to make the articles thereon accessible but will not tilt far enough to either side to spill the articles.

Still further, the present invention proposes constructing the side wall and bottom wall liner and the article holding center member with transparent open top pockets having finger purchase access openings to facilitate putting articles in the pockets and removing them therefrom as well as quick identification of the articles.

As a further object, the present invention proposes an efficient but inexpensive construction and a novel arrangement selectively to hold the hinged article holding center member at different angular positions in the handbag.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view illustrating the handbag of the present invention.

Fig. 2 is a sectional view taken on line 2—2 of Fig. 1.

Fig. 3 is a fragmentary front view of the article holding liner.

Fig. 4 is an enlarged sectional view taken on line 4—4 of Fig. 3.

Fig. 5 is a view similar to Fig. 2 showing the article holding center member tilted to one side and with its other side position indicated in dot-dash lines.

Fig. 6 is a fragmentary perspective view with parts broken away of a handbag and illustrating a modification of the present invention.

Fig. 7 is a top plan view of parts shown in Fig. 6.

The handbag 15, in accordance with the first form of the invention illustrated in Figs. 1 to 6, inclusive, has a bottom wall 16, side walls 17 and

2

18 and end walls 19 and 20. A top flap 21, a clasp 22 and handles 23 and 24 are also shown in Fig. 1.

An article holding side wall and bottom wall liner 25 is fastened to the side walls 17 and 18 of the bag extending across and resting on the bottom wall 16. Liner 25 has a stiffener sheet 26 which may be made of plastic, fiber compositions or similar material. Side sections 27 and 28 of stiffener sheet 26 are secured to the side walls 17 and 18 respectively and the bottom section 29 of the stiffener sheet 26 rests on the bottom wall 16.

A limp sheet 30, of leather, satin, moire, silk, thermoplastic or the like, is secured to and covers the unsecured face of the stiffener sheet. The central part of limp sheet 30 also covers and is secured to a second stiffener sheet 31 to provide a center member 32 hinged by the limp sheet 30 to the liner 25 perpendicular to its bottom section or portion 29.

Pocket forming flexible sheets 33 and 34 preferably of transparent material such as clear thermoplastic sheeting, are secured along their side edges 34, 35, 36 and 37 and along their bottom edges 38 and 39 to the limp sheet 30 on the side wall sections 27 and 28 of the stiffener sheet 26 respectively. The flexible sheets 33 and 34 are also secured to the limp sheet 30 at spaced intervals between the side edges 34 and 35 and 36 and 37 to form article holding pockets such as comb pocket 40, coin purse pocket 41, and wallet pocket 42 on one side of the handbag and note book pocket 43, pen pocket 44, pencil pocket 45, file pocket 46, and key case pocket 47 on the other side. These open top pockets provide article retaining means on the sides of the handbag increasing the capacity of the bag and making the articles therein more readily accessible.

The center member 32 has similar article retaining means on it to hold articles to it. Sheets 49 and 50 of flexible material similar to sheets 33 and 34 are secured to the limp sheet 30 on sides 51 and 52 of the hinged center member 32 respectively. The end edges 53, 54, 55 and 56 of the sheets 49 and 50 and their bottom edges 57 and 58 are secured to the limp sheet 30. In addition, the sheets 49 and 50 are further secured at spaced intervals between their ends to form article holding pockets such as handkerchief pocket 59, match packet pocket 60, cigarette package pocket 61 on side 51 of the center member and compact pocket 62, rouge case pocket 63, lipstick case pocket 64 and mirror pocket 65 on the other side 52 of the hinged center member 32.

Finger purchase openings 66 in the form of V-shaped notches are provided in the pocket forming flexible sheets along their upper edges at the pocket openings.

The center member 32 is hinged and held by the limp sheet 30 so that it may tilt in either direction toward the side walls of the bag but the hinge portions 57 of the limp sheet 30 will not permit the center members to tilt at an angle great enough to spill articles from the pockets 58-65. This angle should be no greater than 45° from the perpendicular and preferably less as shown in Fig. 5. The side walls of the handbag may be positioned to provide rests for the center member if desired.

The modified form of the invention shown in Figs. 6 and 7 is characterized by the provision of a holding means selectively to hold a hinged center member 32' at different angular positions in the handbag 15. This means is comprised of an extendable strap 67, preferably of metal, bridging the side walls 17' and 18' of the handbag and secured thereto. The strap has two end sections 68 and 69 slidably held by bands 70 to a center section 71. Lugs 72 on the end sections prevent them from being pulled out of the bands. The bands are secured to the center section. A slide opening 73 is provided in the center section 71 of the strap 67 and a pin 74 is fixed to the hinged center member 32' and positioned to be slidable in the slide opening of the strap. A plurality of spaced stop grooves 75 are formed in the center section adjacent to the slide opening along its lower edge to receive the pin 74 and removably hold the center member tilted at different angles in the handbag. The center section is lifted up slightly to raise the pin 74 from a stop groove and seat it in the slide opening to move it to another position.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A handbag comprising a bottom wall, side walls and end walls, a side wall liner fastened to the side walls and extending across the bottom

wall, and a center member hinged to the liner perpendicular to its bottom portion and tilttable at an angle, said center member having article retaining means thereon to hold articles to it, and

5 article retaining means on the side walls of the liner adjacent the center member to hold additional articles, and means including an extendable strap bridging the side walls of the handbag and adjustably coupled to said hinged center member selectively to hold the hinged center member at different angular positions in the handbag.

2. A handbag comprising a bottom wall, side walls and end walls, a side wall liner fastened to the side walls and extending across the bottom wall, and a center member hinged to the liner perpendicular to its bottom portion and tilttable at an angle, said center member having article retaining means thereon to hold articles to it, and article retaining means on the side walls of the liner adjacent the center member to hold additional articles, an extendable strap bridging the side walls of the handbag and secured thereto, a slide opening in the strap, a pin secured to the hinged center member and slidable in the slide opening of the strap, and a plurality of spaced stop grooves in the strap adjacent the slide opening to receive the center member pin and removably hold the hinged center member tilted at different angles in the handbag.

3. The combination of claim 2 wherein said strap consists of a center section and end sections and said center section includes bands secured at each end thereof, said end sections 35 passing through said bands, and lug means on the extremities of said end sections, said lugs acting as stops with respect to said bands when the bag is extended.
